Primary Examiner — Karen S Acker*Assistant Examiner* — Jasmine Mlinarcik(57) **CLAIM**

The ornamental design for a necktie, as shown and described.

DESCRIPTION

FIG. 1 is a front elevation view of the necktie;
FIG. 2 is a rear elevation view of the necktie; and,
FIG. 3 is a front elevation view of the necktie, when worn. The broken lines illustrating the human figure depict environmental subject matter that forms no part of the claimed design.
